(57) **CLAIM**

The ornamental design for a vehicle storage door, as shown and described.

DESCRIPTION

FIG. 1 is a front view of the vehicle storage door showing our new design;

FIG. 2 is a rear view thereof;

FIG. 3 is a right side view thereof;

FIG. 4 is a left side view thereof;

FIG. 5 is a front, right, lower corner perspective view thereof;

FIG. 6 is a front, left, lower corner perspective view thereof;

FIG. 7 is a front, right, upper corner perspective view thereof; and,

FIG. 8 is a front, left, upper corner perspective view thereof. The dashed broken lines represent boundaries of the design; the dashed broken lines themselves and the areas within form no part of the claimed design.
